UNITED STATES PATENT OFFICE.

ALBERT BALL AND HENRY H. MERCER, OF CLAREMONT, NEW HAMPSHIRE, ASSIGNEES,
BY MESNE ASSIGNMENTS, TO SULLIVAN MACHINERY COMPANY, OF BOSTON, MASSACHUSETTS, A CORPORATION OF MASSACHUSETTS.

CHANNELING-MACHINE.

1,188,140.

Specification of Letters Patent. Patented June 20, 1916.

Application filed August 20, 1907. Serial No. 389,362.

To all whom it may concern:

Be it known that we ALBERT BALL and HENRY H. MERCER, both citizens of the United States, and residents of Claremont, 5 in the county of Sullivan and State of New Hampshire, have invented an Improvement in Channeling-Machines, of which the following description, in connection with the accompanying drawings, is a specification, 10 like characters on the drawings representing like parts.

Our invention relates to channeling machines, being particularly intended to increase the working efficiency of such machines. 15

Although our invention may be variously applied, we have herein illustrated the same as embodied in a track channeler having a wheeled truck, at the edge of which there is 20 mounted side by side a pair of channeling units which in the present instance consist of pressure fluid engines and tool-connected piston, but so mounted that they may be simultaneously moved for any desired or 25 usual adjustment.

In efforts to increase the working capacity of channelers it has been attempted to increase the size or number of the channeling tools connected to a single engine as well 30 as the power and capacity of such engine. It has been found, however, that there is a limit to the size of the tool gang for a single channeling unit, which limit, if surpassed, results in a rapid deterioration in the quality 35 or excellency of the work accomplished.

The present invention has for its object to increase the working capacity of a track channeler by providing two or more units, each provided with a tool gang of ordinary 40 size, said units being so associated with each other and the machine that they may be readily used upon a track channeler in substitution for a single unit, such as is now generally employed, while substantially 45 doubling or more than doubling the working capacity thereof and at the same time obtaining increased efficiency and superior results.

Our invention will be best understood by 50 reference to the following description when taken in connection with the accompanying illustration of one specific embodiment thereof, while its scope will be more particularly pointed out in the appended claims.

In the drawings: Figure 1 is a front elevation of a channeling machine embodying one form of our invention; Fig. 2 is a similar view showing a modified form of tool-feeding mechanism; Fig. 3 is an end elevation of the channeling machine shown in Fig. 1; Fig. 4 is an end elevation of a modified form of the machine; Fig. 5 shows the relation of the controlling valves for the two engines; and Fig. 6 shows the construction of the brace bars for the machine shown in Fig. 4.

Referring to the drawings, and particularly to Figs. 1 and 3, while our invention may be usefully embodied in channeling and other machines of various and different types, we have here shown a form of track channeling machine comprising the main truck or frame 1 mounted upon the wheels 2, the latter adapted to move upon the usual rails 3 laid along the quarry bottom.

The truck may be propelled in any suitable way but herein it carries a track-driving motor or engine 4 and usually a boiler (the latter not shown), the engine crank-shaft 5 being connected through the reversing gearing 6, clutch shaft 12, spur gear 7, worm shaft 8 and worm gears 9 with the truck axles 10, whereby the truck may be driven under its own power. The clutch lever 11 is constructed and connected to clutch 88 the shaft 12 to one or the other of the two oppositely driven bevel gears of the reversing gearing 6 to effect movement of the truck in either direction. Such gearing may be of any suitable or usual construction and is 90 unnecessary to describe in further detail, the same herein being of the general principle disclosed in U. S. patent to Ball, No. 392,398.

While the channeling units may be carried on the truck in any suitable manner, there is 95 here shown, supported at the working side of the truck, the supporting plate 13 serving adjustably to carry the upright standard 14. The plate is mounted for a limited angular adjustment away from the vertical 100 plane, being provided at either end with a longitudinal depending supporting member 15, which is fulcrumed in a groove in the truck frame, in which it is held down by means of the bolts 16 and clamps 17. The 105 clamp may be loosened and the plate tipped back for angle cutting through adjustment of the stay or brace rods 18. The front face

of the supporting plate is provided with horizontal T slots 19, to which the standard 14 may be bolted, being adjustable to either end of the truck or any other intermediate position.

Referring now to the channeling units, the latter are two in number, although more may be employed if desired. While other forms of motive devices for reciprocating the channeling tools may be employed, we have therein shown ordinary and usual constructions of pressure fluid engines having their cylinders 20, 21, together with the cross-head guides 22, 23, which act to guide the tool-carrying cross-heads 24, 25, all mounted upon and carried by a vertically adjustable frame 26. The latter is gibbed to slide upon longitudinal finished ways 27 upon the standard, and the upper end of the cylinder casting is attached to the lower end of the feed adjusting screw 28, so that through the latter the cylinders, frame and tool gangs may be advanced or retracted relatively to the work.

Any suitable means for feeding the tools in the manner set forth may be employed, but herein we have provided a threaded nut secured to the beveled gear 31 and held against longitudinal movement by the standard 14. The nut and gear are turned by the sprocket wheel 32, the latter being driven through the chain 33 and the engine 4, so that the latter is available to feed the tool toward or from the work, a controlling lever 34 being employed to start, stop and reverse the tool feed.

In Fig. 2 we have shown a modified construction of feeding mechanism, the same differing from that described in the provision of two feeding screws 28, each connected to cylinders and in the axial line of its respective cylinder and each engaging with a threaded nut supported in the arch of the standard and turned through the medium 45 of the intermeshing gears 35 and 36. This brings the resistance of each feeding screw directly in the line of blow of each engine.

Power in the form of steam or other pressure fluid may be supplied for the engine, either from a boiler, which may be carried upon the truck, or from any other suitable source, from which it is led to the pressure chest of the engines by connections not shown.

In order that the two sets of tools may work together in some measure of synchronism, we have herein shown the valves of the two engines so connected that the reversing valve of one is controlled by the reciprocatory movement of the other, thereby keeping them in reversed relation or opposed step; that is to say, as one gang moves up the other moves down and vice versa.

Referring to Fig. 1, the reversing valve 65 for the left hand engine 21 has its stem 37

connected to the lever 38, which latter has one end pivoted to the frame 26, and its opposite end connected by the link 39 to the right-hand cross-head 24. Likewise the stem 40 of the reversing valve for the right-hand engine 20 is connected by means of the lever 41 and the link 42 to the left-hand cross-head 25. By this means the downward movement of the right-hand cross-head causes downward movement of the reversing valve for the left-hand engine, so that a reversal of the latter from an upward movement to a downward movement takes place at or near the center of the downward movement of the right-hand cross-head. The right-hand engine is controlled in a like manner from the left-hand cross-head. This insures synchronism in the movement of the two engines and the action of the two tool gangs in opposed step.

While the detailed construction of the valves is immaterial, and our invention is not limited to any particular form or arrangement thereof, we have shown in Fig. 5, without reference to constructional accuracy, the general scheme or arrangement of passages by which this control is effected. Such scheme or arrangement shows the usual form of main controlling valve for each cylinder, the controlling valve, however, in each case being reversed by pressure admitted through the medium of an auxiliary reversing valve controlled by the cross-head of the companion engine instead of its own cross-head, as is customary.

The general arrangement of valves will be apparent by reference to Fig. 5, a detailed description of the reversing and controlling valves for one cylinder only being necessary since the details of the construction of the valves for the other cylinder are substantially similar. Referring to the valves controlling the right-hand cylinder, live steam or other pressure is admitted from any convenient source to the reversing valve chamber 43 for the right-hand engine and thence admitted to the upper or lower passages 44, 45, leading to opposite ends of the main controlling valve 46 for the right-hand cylinder. The control of said passages and also of the exhaust passage 47 is effected by the slide valve 48 controlled by the valve stem 40, so that when the said stem moves downward as shown in the drawings the passage 45 is connected to the exhaust 47 and the passage 44 to the live pressure, thereby forcing the controlling valve 46 downward into the position shown. This admits pressure from the pressure chamber 49 of the reversing valve for the left-hand cylinder to the upper cylinder-admission-port 50 through the intermediate port 51, the lower cylinder-exhaust-port 52 being connected with the space 53 in the controlling valve chamber, which has per-

manent connection with the engine exhaust. Lost motion is provided between the slide valve 48 and the valve stem 40, so that the reversal of the controlling valve 46 does not 5 take place until the close of the downward movement of the valve stem 40. At the close of the upward movement of the valve stem 40 the passage 45 is connected with the pressure, and passage 44 with the exhaust, 10 thereby lifting the controlling valve 46, admitting pressure to the lower cylinder-admission-port 54 and exhausting the same through the upper cylinder-exhaust-port 55.

Precisely the same control over the left-hand engine is effected by the movement of the valve stem 37, the only difference being that the two movements are reverse or opposite.

As the machine travels along the track, for example, from left to right, the right-hand gang will first reach the vertical end of the cut. This will leave a short portion of the cut equal to the distance between the inner sides of each gang, over which only one gang has passed, and in which the cut is therefore shallower than the remaining portion of the channel groove. To cut this distance down to its proper level it is necessary to traverse the machine back while operating the right-hand gang. During this operation the left-hand gang should not strike the bottom of the cut. To prevent this we have provided a cushioning valve for each engine in the form of a gate 56 (Fig. 5) which may be operated by the handle 57 from the rear of the cylinder and turned to throttle more or less the exhaust passage. If, under the conditions assumed, the cushioning valve is thrown in, the downward stroke of the left-hand engine will be cushioned, allowing its gang to miss the rock, while the right-hand gang will continue to cut. In order to throttle more or less the admission and exhaust for both sets of each cylinder, additional throttle valves or gates 58, 59 and 60 are shown (Fig. 5).

With the construction described, which contemplates the employment of a single frame for the two engines, with the cross-head and cross-head guides closely adjacent, the distance between the two gangs of tools is kept down to a minimum, so that the amount of over-cutting as described is comparatively small.

While in the construction shown in Fig. 1 simultaneous adjustment of the two cylinders may be effected either lengthwise the truck or at an inclination lateral thereto, 60 we have shown in Fig. 4 a modified construction in respect to the movement of the standard upon the truck, which modified construction is advantageous for angle cutting. In the construction shown in Fig. 4 65 the standard is represented at 61 and is

swivelled directly upon the trunnion shaft 62 extending lengthwise the machine. The standard is provided with a clamping cap 63, whereby it may be clamped to the trunnion shaft in any position lengthwise the same, and at any desired angle or inclination from the vertical. 70

One feature of novelty in the machine illustrated in Fig. 4 is the provision of one or more brace members, herein two, which are so arranged that when the standard is moved lengthwise the machine from one end of the truck to the other the brace members may be moved with the same without the necessity of first detaching them from the standard or from the truck. Referring to Figs. 4 and 6, the standard is provided with a pair of threaded brace rods 64, one at either side thereof, which have threaded engagement with a split clamping member 65. The clamping members are swiveled at opposite ends of the split sleeve 66, which latter is mounted to slide along the shaft 67 parallel with the trunnion shaft. When the standard is to be adjusted the clamping bolts 68 on the sleeve 66 are loosened and the latter can be slid along the shaft 67 with the standard, thus greatly facilitating the adjustment of the machine.

The employment of a plurality of tool-actuating units suitably associated in some such fashion as herein described, where they are so arranged as to oppose each the reactionary effect of the other upon its support, not only tends to reduce the vibration and shock within the machine itself through the balance secured between the operating parts, but also reduces the tendency to lateral displacement of the machine and the tools within the cut. 95 100 105

In the case of a channeling machine of the type illustrated if it were fitted with a single tool-actuating cylinder only, as heretofore, each reversal in the reciprocatory movement of the heavy tool gang imparts a reactionary shock or thrust to the machine. Such thrust, occurring as it does (in the direction of cutting) at one side of the truck and offset from the center of gravity of the latter, vibrates and rocks the machine and tends to lift first one side of the truck and then the other from the rails. This vibratory or rocking movement of the machine is not only disadvantageous of itself, but acts to oscillate the tools from side to side with- 110
115
120

in the cut as they are reciprocated and advanced. This not only results in an imperfect cut and quickly dulls the cutting edges as well as the sides of the tools through their frictional contact with the sides of the channel, but the frictional resistance to the tools caused thereby requires a greater expenditure of power both for the tool reciprocation and the power-fed advance of the machine.

By the employment of a plurality of tool-actuating units maintained in out-of-step reciprocation as,—for example, the two channeling engines described which are reciprocated out-of-step and in direct opposition,—the unbalancing effect of each unit upon the support is offset by the opposed unbalancing effect of the other, and the side-wise vibration or rocking movement being 5 eliminated or materially reduced, the tools may be retained against cramping action in the kerf during the process of cutting. Furthermore, in the case of a channeler having a single tool-actuating unit, the reactionary 10 shocks referred to not only manifest themselves in the rocking movement described, but these shocks, being transmitted through the feed screw and the standard to the support, and through all the connections by 15 which the various angular and other adjustments of the tools are effected, not only require the supports and connections intermediate the truck and the tools to be of great 20 strength for withstanding the resultant vibratory strains, but tend to keep the parts of the entire machine, while in operation, 25 in a state of excessive vibration.

In the case of the balanced machine described, since the reactionary effect of one 30 cylinder tends to offset that of the other, and the cylinders are rigidly connected to be adjusted as a unit, the vibration and shocks referred to are absorbed largely or wholly within the rigidly connected cylinders themselves, and within the sliding frame to which they are attached, thereby relieving the feed 35 screws, standard, brace rods and other connections by which the standard is adjustably secured to the truck, from the excessive vibration of a machine employing a single cutting 40 unit. On this account not only may the various adjustments of the cutting tools be secured by connections having the maximum of rigidity with the minimum of lightness, but each unit may be operated at a 45 much higher speed than in the case of the single unit machine. Since the greatest efficiency in cutting a channel is secured at higher speeds than can be attained in practice with a single unit machine, due to the 50 excessive vibration of the parts referred to, the illustrated form of machine, by permitting the attainment of a higher speed, secures a correspondingly better cutting efficiency.

It has been found in actual practice that not only does the described disposition and relation of cutting units substantially eliminate the side or cross swing of the tool gang, 55 which is due to the transverse rocking of the truck-mounted machine, but in a machine like that herein illustrated there is actually introduced a longitudinal swing of the tool gang in line with the channel groove, due

to the slight rocking movement of the machine lengthwise the trackway as the tools alternately strike the bottom of the cut. This provides in effect the same roll or swing which is imparted to a channeling tool in hand cutting, which roll or swing, so far as 60 we are aware, has never been secured by any prior form of power driven channeler. This roll or swing of the tool gang provides the most efficient form of cutting action and also tends to keep clear the bottom of the 65 cut of chips and dust.

While, for the purpose of illustrating one concrete embodiment of our invention, we have shown the same as embodied in a stone channeling machine of a particular type and 70 construction, many features of the invention, with their attendant advantages, may be applied to channeling machines of other types and constructions as well as stone working machines other than channeling 75 machines.

While we have herein shown and described one form of our invention for illustrative purposes, it is to be understood that the same is not limited to the particular 80 form or relative arrangement of parts, but that extensive modifications may be made in the same without departing from the spirit of our invention.

Claims.

1. A channeling machine having a wheeled truck, a pair of channeling engines substantially rigidly mounted in relatively close relationship at the side thereof in a position to cut a downwardly disposed channel groove 95 parallel with the direction of travel of said machine, said engines being mounted one in advance of the other, a reciprocatory tool-carrying cross head for each engine, a reversing valve for each engine and connections between the reversing valve of each engine and the cross head of the other engine whereby each engine is reversed by the movement of the other and the two engines maintained in substantially simultaneous opposed 100 step, thereby to prevent the sidewise rocking movement of the truck and maintain the channeling tools in alignment with the intended cutting plane.

2. A channeling machine containing, in 115 combination, a wheeled truck adapted to run upon a suitable trackway along a supporting surface, a pair of reciprocatory tool-actuating devices, substantially rigid supporting means for directing the tools to cut a continuous kerf at the side of the truck transverse to the plane of the supporting surface, said tool-actuating devices being located in 120 relatively close relationship side by side one in advance of the other in the direction of travel of the truck, and means to substantially simultaneously reciprocate said devices 125 in reverse relation whereby they offset each

the unbalancing effect of the other upon the supporting means and the truck and retain the tools against cramping action in the kerf during the process of cutting.

5 3. A channeling machine containing, in combination, a wheeled truck adapted to run upon a suitable trackway along a supporting surface, power-actuated means thereon for advancing said truck during the operation

10 of the machine, a plurality of reciprocatory tool-actuating devices, substantially rigid supporting means for directing the tools to cut a continuous kerf at the side of the truck transverse to the plane of the supporting

15 surface during the power-fed advance of the machine, said devices being located in relatively close relationship side by side and one in advance of the other, and means for causing the reciprocation of said devices in

20 substantially simultaneous relatively timed out-of-step relation whereby they offset each the unbalancing effect of the other and retain the tools against cramping action in the kerf during the process of cutting.

25 4. A stone working machine having a movable support, a plurality of tool-actuating devices substantially rigidly sustained at one side thereof and so directed as to cut transversely to the horizontal plane, said devices

30 being located in relatively close relationship one in advance of the other, thereby to cut a continuous channel groove in the direction of movement of the support, and means for imparting a substantially simultaneous re-

35 ciprocating movement to said devices in out of step substantially balanced relation, thereby to cause said devices each to offset the unbalancing effect of the other or others on the said support.

40 5. A channeling machine having a truck, a standard mounted at the side of the truck and carrying a channeling unit, means for rigidly but adjustably holding the standard at its lower end whereby it may be adjusted

45 from one end of the truck to the other, a brace member adapted to have one end secured to the standard near its upper end and its opposite end secured to the truck near the opposite side of the truck from the

50 standard and adapted to act as a brace for said standard during the cutting operation of the machine, and means adjustably securing the truck-connected end of the brace member whereby it can be adjusted length-

55 wise the truck without detachment from the truck.

6. A channeling machine having a truck, a standard mounted at the side thereof carrying a channeling unit, means adjustably

60 securing the standard to the truck for adjustment of the same lengthwise the truck and also for adjustment thereof backward over said truck for angle cutting, comprising a brace member secured near the upper

end of the standard, a sleeve to which said brace member is attached and a shaft running lengthwise the truck along which said sleeve is adapted to slide.

7. A channeling machine having a wheeled truck, a pair of reciprocatory tool-actuating devices, substantially rigid mountings for supporting said devices at the side of the truck in upright position, said devices being located in relatively close relationship one in advance of the other in the direction of travel of the truck, thereby to cut a continuous channel groove, means for feeding the truck, and means for operating said devices in substantially simultaneous reverse relation to produce a balanced effect upon the truck, transverse the same and an unbalancing effect upon the truck lengthwise the same, thereby to prevent the sidewise swinging movement of the tool while imparting a swing to the tool lengthwise the channel groove.

8. In a channeling machine, the combination with a truck adapted to run upon a suitable supporting surface, a plurality of reciprocatory tool-actuating devices, a common support for said tool-actuating devices

90 directing the tools to cut a continuous kerf at the side of the truck, said tool-actuating devices being located in relatively close relationship side by side one in advance of the other in the direction of travel of the truck,

95 means for adjustably inclining the said support and thereby simultaneously adjusting said tool-actuating devices to vary the angle of cut, and means for reciprocating said devices in substantially simultaneous opposed step relation whereby they offset each the reactionary effect of the other upon the said

100 common support and the truck.

9. A channeling machine having a truck 105 adapted to run upon a suitable trackway along a supporting surface, a plurality of reciprocatory tool-actuating devices, a common upright support to which said devices

110 are attached, said devices being located in relatively close relationship side by side and one in advance of the other, thereby to cut a continuous channel groove in the direction of travel of the truck, means for adjusting said support together with said devices

115 as a unit on the truck toward or from the work, and means for reciprocating said devices in substantially simultaneous, relatively timed, out-of-step relation whereby they offset each the reactionary effect of the other on the said support and its attachment to the truck.

10. A channeling machine having a truck adapted to run upon a suitable trackway along a supporting surface, a plurality of reciprocatory tool-actuating devices thereon, a common upright support for said tool-

125 actuating devices, said devices being located

in relatively close relationship side by side on said support and one in advance of the other, thereby to cut a continuous kerf in the direction of travel of the truck, means 5 for securing said support to either end of the truck to cut a continuous kerf at the side of the truck and at the leading end thereof, and means for reciprocating said tool-actuating devices in substantially simultaneous out-of-step relation, thereby to offset 10 each the reactionary effect of the other and confine such reactionary effect to the common support.

11. A channeling machine having a movable support, tool appliances, a plurality of tool-reciprocating devices carried by said support, side by side and one in advance of the other to cut a continuous channel groove, means for reciprocating said devices simultaneously in relatively timed relation, and means for temporarily rendering either of 20 said devices inoperative while permitting the cutting operation of the other.

12. A channeling machine having a plurality of pressure fluid-operated, tool-actuating devices, traversing means on which the same are mounted to cut a channel groove, said devices being located one in advance of the other, thereby to cut a continuous channel groove in the direction of movement of the support, means for applying the pressure fluid to maintain said devices simultaneously operating in an opposed step relation whereby they offset each the unbalancing effect of the other, and means for 30 controlling the fluid to render one of said devices temporarily inoperative while permitting the cutting operation of the other.

In testimony whereof, we have signed our names to this specification, in the presence 40 of two subscribing witnesses.

ALBERT BALL.
HENRY H. MERCER.
